SUPPORTING DEVICE

William G. Leichner, Fort Wayne, Ind., assignor
to Farnsworth Television and Radio Corpora-
tion, a corporation of Delaware

Application April 30, 1942, Serial No. 441,217

4 Claims. (Cl. 248—309)

This invention relates generally to a means for supporting the circuit elements in electronic apparatus and more particularly to supporting devices for chassis-borne elements such as condensers, resistors and coils in radio circuits or public address systems.

Electronic radio or sound reproducing equipment is frequently installed in motor vehicles or in factory structures where excessive vibration and jarring motions occur. To obtain efficient operation of the circuits in this radio and sound reproducing equipment, it is necessary that such provisions be made that the circuit connections may be maintained in substantially perfect condition to eliminate failures or imperfect operation. To accomplish this result, it is essential that the circuit elements such as coils, resistors and condensers be firmly supported with respect to the main chassis or to the rack or panel equipment which is customarily used for supporting radio and sound amplifying equipment. In meeting this problem, it is also necessary that whatever support elements may be used should involve simple manufacturing operations, minimum quantity of material and general economy of production.

Accordingly, the object of this invention is to provide a novel supporting device for electric elements such as resistors, coils and condensers, particularly adapted to withstand the effects of vibratory and jarring motions. It is a further object of this invention to provide a support of this character which costs little and is simple to manufacture.

For a better understanding of the present invention, together with other and further objects thereof, reference is had to the following description taken in connection with the accompanying drawing and its scope will be pointed out in the appended claims.

Referring to the drawing:

Fig. 1 of the drawing is a front view of one embodiment of this invention illustrating a supporting device particularly adapted to support a condenser element;

Fig. 2 is a side view of the embodiment shown in Fig. 1;

Fig. 3 of the drawing is a front view illustrating a second embodiment of this invention;

Fig. 4 is a side view of the embodiment shown in Fig. 3;

Fig. 5 of the drawing is a top view of a third embodiment of this invention; and

Fig. 6 is a view from a direction indicated by arrows 6—6 in Fig. 5.

Referring to Fig. 1 of the drawing there is shown a portion of a chassis or base plate 1 to which is attached a right angle plate member 2 by the nut and bolt assemblies 3 and 4. The element supported from the right angle member 2 is illustrated, by way of example, as a condenser 5 of well-known configuration which is bolted to the vertical portion of plate 2 by a screw member 7. There is provided a cam or eccentric 8 adapted to be tightened into the position shown in Fig. 1 by a screw 10.

The method of assembly of the apparatus shown in Fig. 1, consists of attaching condenser 5 to the upright portion of plate 2 by tightening the screw 7 and thereby drawing condenser 5 tightly to the right angle member 2 in such a position that one of the flat surfaces of condenser 5 bears against the horizontal surface of right angle plate 2 as shown in Fig. 1. The support is rendered vibrationproof by rotating the cam or eccentric 8 toward condenser 4 until condenser 5 bears solidly against the horizontal surface of plate 2. By tightening the screw 10 to maintain cam 8 in the position shown in Fig. 1, there is maintained such a pressure on condenser 5 that a transverse force is imparted to screw 7, thereby preventing it from loosening and the lower surface of condenser 5 is maintained in solid relation with respect to the horizontal surface of right angle plate 2. Thus, regardless of the degree of vibration to which chassis 1 may be subjected, condenser 5 can not have any motion with respect to chassis 1 or right angle plate 2.

The preferred embodiment of the invention is illustrated in Fig. 3 which is similar to Fig. 1 in that condenser 5 is supported on a right angle plate member 2 which is attached to chassis 1. The assembly is rendered vibration proof by means of a somewhat resilient lug 12 which is cut out of the upright portion of plate 2 and bent outwardly therefrom to such a position that it is substantially at right angles to plate 2. However, the angle of lug 12 with respect to plate 2 should be such that it will not permit perfect alignment of the threaded hole in condenser 5 with screw 7. Therefore, condenser 5 must be forced into alignment against resilient lug 12 whereby screw 7 may be screwed into the threaded hole in condenser 5. When screw 7 is tightened to draw condenser 5 to its proper position, lug 12 imparts a transverse force to condenser 5 and screw 7. Thus, by adjusting the angle of lug 12 with respect to plate 2, any desired degree of transverse pressure may be brought to bear on condenser 5 whereby it rests firmly on the hori-

zontal surface of plate 2 and screw 7 is bound or jammed in the tight position.

Fig. 5 illustrates a third embodiment of the invention including chassis member 1 to which the condenser element 5 is fastened directly by screw 7. In assembling this modification of the invention, condenser 5 is placed on chassis 1 with surface 9 of condenser 5 in contact with the surface of post 11. For rendering this assembly vibrationproof, there is provided a tapered element 13 which is bolted to chassis 1 by bolt and nut assembly 14. The tapered element 13 is bolted to chassis 1 in such relation to condenser 5 that tapered element 13 positively engages condenser 5 and imparts pressure thereto. Thus, condenser 5 bears firmly on post 11 to bind screw 7 and prevent any loosening of screw 7 or of condenser 5.

This invention has been illustrated as it may be applied to a support for a condenser element, but it will be obvious to those skilled in the art that any other circuit element, such as a resistor or coil, may be provided with a vibrationproof support so long as it is supported in such a manner that one of its surfaces bears against the support and another of its surfaces bears against a resilient or adjustable element whereby a transverse force may be applied to prevent any loosening of the supporting screw or the entire element. It will also be obvious to those skilled in the art that there are many other possible constructions of the supporting element which will accomplish the desired result. There is, for instance, in the case of the embodiment illustrated in Fig. 3, a possibility of substituting for lug 12 a bent portion of the horizontal part of plate 2 or a bent portion of the vertical part of plate 2. The desirability of whatever modification of the invention may be used depends upon the configuration of the supported element and the conditions under which the chassis is to be used.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

I claim:

1. A support adapted to withstand vibratory or jarring motions comprising a main supporting member having a pair of surfaces at right angles

to one another, an adjustable fastening element in one of said surfaces for securing a supported member thereto and means adjacent said fastening element and in position to engage said supported member for imparting a transverse force to said fastening element and said supported member thereby to force said supported member into engagement with the other of said surfaces and prevent said fastening element from changing its adjustment under the influence of vibratory and jarring motions.

2. A support adapted to withstand vibratory or jarring motions comprising a main supporting member having a pair of surfaces at right angles to one another, an adjustable fastening element in one of said surfaces for securing a supported member thereto and resilient means adjacent said fastening element and in position to engage said supported member for imparting a transverse force to said fastening element and said supported member thereby to force said supported member into engagement with the other of said surfaces and prevent said fastening element from changing its adjustment under the influence of vibratory and jarring motions.

3. A support adapted to withstand vibratory or jarring motions comprising a main supporting member having a pair of surfaces at right angles to one another, an adjustable fastening element in one of said surfaces for securing a supported member thereto and tapered means adjacent said fastening element and in position to engage said supported member for imparting a transverse force to said fastening element and said supported member thereby to force said supported member into engagement with the other of said surfaces and prevent said fastening element from changing its adjustment under the influence of vibratory and jarring motions.

4. A support adapted to withstand vibratory or jarring motions comprising a main supporting member having a pair of surfaces at right angles to one another, an adjustable fastening element in one of said surfaces for securing a supported member thereto and eccentric means adjacent said fastening element and in position to engage said supported member for imparting a transverse force to said fastening element and said supported member thereby to force said supported member into engagement with the other of said surfaces and prevent said fastening element from changing its adjustment under the influence of vibratory and jarring motions.

WILLIAM G. LEICHNER.
